MAGAZINE LOADED RECOILLESS GUN

Charles Dennistoun Burney, Baynards Park,
near Cranleigh, EnglandApplication September 6, 1945, Serial No. 614,719
In Great Britain October 4, 1943Section 1, Public Law 690, August 8, 1946
Patent expires October 4, 1963

11 Claims. (Cl. 89—1.7)

1

The present invention relates to recoil-less guns of the type forming the subject matter of my prior but concurrent application for Letters Patent Serial No. 552,347 now Patent No. 2,489,747, and adapted for quick firing with automatic loading in accordance with my applications for Letters Patent Serial Nos.: 614,717 and 614,718, filed of even date herewith, and now Patent No. 2,489,954 and now abandoned, respectively.

In the two last mentioned applications the rearwardly discharging gases for balancing the recoil are discharged through a pair of spaced nozzles, extending beyond the breech from lateral enlargements of the cartridge chamber, the projectiles being loaded into a breech aperture lying between the nozzles, and the charges either being loaded behind the projectiles, or being loaded into the opposite ends of the lateral enlargements in the reverse direction to the projectile.

According to one feature of the present invention, a carrier for a number of projectiles is rotatably arranged on one of the projecting nozzle members, said carrier having a number of axially extending sockets or holes to receive the projectiles, and the projectiles, loaded into the carrier at a loading point, are carried round step by step until they come opposite to the breech chamber between the nozzles, when a co-operating automatic ramming device is actuated to ram the projectile home in the breech chamber. The carrier may be rotated by hand with a step-by-step motion, but for quick firing may be automatically rotated, as, for instance, in a manner similar to the indexing of a capstan lathe turret.

Broadly therefore the invention comprises a recoil-less gun of the type specified having a pair of gas discharge nozzles spaced apart, with the breech opening between them, the ammunition being supplied through the medium of a carrier rotatable on one of the gas nozzles and being transferred into the breech from said carrier by a moving breech block reciprocated by gas pressure derived from the gun barrel in one direction and a return spring in the other direction. The carrier may be an annular magazine carrier removable from the nozzle and carrying a plurality of rounds of ammunition disposed peripherally thereof, or the ammunition may be supplied to the carrier by a belt of ammunition passing thereover.

2

According to a further part of the invention the carrier is adapted to be rotated by a pawl and ratchet mechanism operated by the reciprocating breech block mechanism. In one construction, for example, the breech block is carried between the arms of a forked member passing through slots in the breech chamber wall and connected to a piston in a gas cylinder communicating with the barrel bore, whilst the fork arms are engaged in curved grooves in a pair of levers fixedly pivoted at one end and articulated to rods connected to a pair of ratchet pawls at their free ends, one of said pawls being operative through an annular ratchet on the end of the magazine carrier to rotate the carrier on the downward movement of said pivoted levers and the other of said pawls being operative to rotate the carrier on the upward movement of said pivoted levers.

20 In order that the invention may be clearly understood and readily carried into practice it is illustrated, by way of example only, in the accompanying drawings, in which:

Figure 1 is a side elevation of an automatically loaded recoil-less gun of 20 mm. caliber according to this invention;

Figure 2 is a plan view thereof;

Figure 3 is a view to a larger scale of the breech end of the gun, showing the magazine operating mechanism only, the breech block and its associated parts being omitted for the sake of clearness;

Figure 4 is a rear elevation diagrammatically showing the magazine and part of its operating mechanism;

Figure 5 is a section showing the breech block construction in detail;

Figure 6 is a partial plan view of the breech block;

40 Figure 7 is a sectional view, to a larger scale than Figures 1 and 2, showing the construction and arrangement of the magazine carrier;

Figure 8 is a detail view in section of the magazine release device therefor;

45 Figure 9 is a view of the pawl rotating mechanism for the magazine carrier;

Figure 9a is a view showing the magazine clutch and release mechanism;

50 Figure 10 is a diagram of the extractor mechanism;

Figure 11 is a sectional diagrammatic view of the double loading step arrangement, and

Figure 12 is a diagram showing a form of ammunition belt suitable for use in connection with the improved gun.

The barrel 1 is screwed into the breech chamber 2, the rear part of which is fitted with two outwardly inclined nozzles 3, which are spaced vertically apart, to leave a clear space behind the breech opening of the chamber 2. Supported from the breech chamber 2 and the upper nozzle 3, is the breech block guide bracket 4, which is connected to the nozzle 3 by a web dove-tailed into the bracket 4. The rear end of this bracket 4 has pivoted thereto a pair of curved tail levers 15 which extend forwardly towards the breech, and near their ends have pivoted thereto rods 16 for operating the magazine carrier as hereinafter described.

Mounted above the barrel 1 is a gas cylinder 6 to which explosion gases are admitted through valve 5 from behind the projectile, as soon as the projectile passes the inlet port of said valve. In the cylinder 6 moves a piston 13 whose spindle 12 extends towards the breech block and forks into a pair of parallel arms 11 which pass through slots in the breech chamber wall where suitably enlarged by lugs (see Fig. 4). The free ends of fork arms 11 are connected to the bracket 9 (Fig. 5) which carries the breech block 10, and also carry on their outside surfaces studs 14 which are engaged in longitudinal grooves along the inner surfaces of the curved tail levers 15. Consequently, as the piston 13 reciprocates, the tail levers 15 are depressed and raised owing to the curvature of their slots, to operate the magazine carrier 26 through the pawl mechanism hereinafter described.

The breech block 10 is of the rotary interrupted screw type, and it is of hollow cylindrical box form, with peripheral external screw threads, helices, or parallel collars, 10a, interrupted at several points, as is well-known. Centrally within the breech block is a sleeve 10b in which slides the firing pin 50, which is mounted on bracket 9, which also carries a concentric sleeve 49 adapted to slide within the skirt of the breech block 10. Surrounding the sleeve 10b, but lying within the sleeve 49 is a spring 51 which acts to move breech block 10 outwardly on sleeve 49. In the outside of wall 49 are helical grooves 31 which are engaged by pins 30 projecting inwardly from the skirt of breech block 10, whilst peripherally the breech block 10 carries a pin 52 engaged in a longitudinal groove in guide bracket 4. As the breech block 10 is moved by fork arms 11 from its extreme rearward position towards the breech the pin 52 prevents relative rotation of breech block 10 in relation to part 49, but when block 10 has been introduced into the breech the slot in which pin 52 travels terminates so that block 10 is then free to rotate. The fork arms 11 still have farther to travel, and this is permitted by spring 51, but in doing this the helical grooves 31 and pins 30 cause rotation of block 10, which is then freed from the restraint of pin 52. Consequently the divided screw threads, helices or collars of breech block 10 become fully engaged with those in the breech end of chamber 2 and the breech becomes tightly closed. The final movement of fork arms 11 cause the point of the firing pin 50 to project through the end of sleeve 10b and strike the cartridge percussion cap, thus firing the gun.

The above movement of the fork arms 11 which inserts the ammunition in the breech, closes the breech block, and fires the gun, is effected by the spring 29 (Fig. 2) in which energy is stored during the rearward stroke of the fork, produced by the gas pressure. The spring 29 surrounds a guide rod projecting from breech chamber 2, which enters into a tube 12a extending rearwardly from the fork of piston rod 12, the forward end of the spring 29 bearing on the rear end of the tube 12a.

The breech block 10 also serves in its forward movement as a rammer for introducing the ammunition into the breech chamber 2, the ammunition being of fixed type, and comprising a cartridge case containing the propellant charge with the projectile fixed at its forward end. Since, however, the present invention is concerned with recoil-less guns in which a large part of the explosive gases is discharged rearwardly through the nozzles 3, the cartridge case must be perforated or of skeleton formation.

The ammunition is fed into the breech from a magazine carrier 26 which is rotatably mounted within a fixed outer casing 26a on the lower nozzle 3, through the intermediary of a cylinder 27 attached by a plate 28 to the nozzle 3. The sheet metal magazine carrier 26 has arcuate spaces or sockets 22a in which the rounds of ammunition are accommodated, between which are rollers 53 adapted to facilitate rotation of the carrier 26 on cylinder 27. At its rear end the magazine carrier 26 has a ring of ratchet teeth 64 (Fig. 9) adapted to be engaged by pawl arms 23 and 23a rotatable about a central pivot 54 on the inside of plate 28. To these pawls are connected the free ends of the rods 16 pivoted to the tail levers 15. On the rearward stroke of the fork arms 11 both pawl levers 23 and 23a are driven downwards by tail levers 15, and the right hand one operatively engages a tooth 64 so as to rotate the carrier 26 for an angular distance equal to half the spacing of the ammunition, whilst the left hand pawl rides over the magazine ratchets. On the return (forward) stroke the tail levers 15 are raised and therewith the pawl arms 23 and 23a are raised, but this time their functions are reversed, inasmuch as the left hand pawl will be operative and the right hand will ride over the ratchets. The carrier 26 will accordingly be carried forward again once more, for the same angular distance as before, bringing the next round of ammunition exactly opposite to the breech, ready for ramming home by the reciprocating breech block 10, as already described.

As shown in Figure 7 the pivot 54 round which the pawls 23 and 23a rotate is hollow and is fitted with a push button 25 adapted to be depressed against an internal spring. The free end of push button rod projecting beyond the pivot 54 has mounted thereon three rings articulated to the radial arms of bell-crank levers 55 pivoted to brackets on the inside of cylinder 27, so that as button 25 is pressed in the bell-crank levers 55 are rotated simultaneously in the rearward direction (anti-clockwise in Figs. 7 and 8). The short arms of the bell-crank levers 55 carry shoes 24 which are adapted to pass through holes in the wall of cylinder 27. When the bell-crank levers 55 move forwardly, the shoes 24 move into engagement with an annular groove or channel 7 formed internally within the removable magazine carrier 26. When the shoes 24 are engaged in groove 7 the magazine carrier 26 is retained.

against axial movement on the cylinder 27, but is permitted freely to rotate thereon, to bring one round after another opposite to the breech for loading and firing until the magazine is exhausted. The magazine shown in the drawings is designed to hold eight rounds, but obviously it could be designed to hold any desired number of rounds. When the magazine carrier 26 becomes empty it is only necessary to press button 25 to retract shoes 24 and free the empty magazine carrier for removal and replacement by a new fully charged carrier.

It should be understood that when the breech block 10 first engages a round in the magazine carrier 26 it does not engage axially therewith, but only engages with an upper lip portion thereof, and that as the round moves forwardly into the breech its rear end rises until finally it is axial in relation to the breech block 10, when this closes the breech.

The cartridge cases are automatically extracted and ejected by the mechanism illustrated diagrammatically by Figure 10. On each side of the breech ring are pivoted extractors 63, which engage behind the cartridge flange on loading and on the spindles of said extractors are mounted externally of the breech chamber wall angularly directed levers 65 the free ends of which are curved to lie in the paths of lugs or projections 66 on the sides of fork arms 11. The said lugs are so located that the extractors are operated to dislodge the cartridge case and throw it clear of the breech as soon as the breech block 10 has moved substantially to the end of its rearward stroke.

In order to guard against the loading mechanism operating on a new round of ammunition should a round fail to be extracted and remain in the breech, a double loading stop device, such as is illustrated by Figure 11, may be provided. This consists of a telescopic spring plunger 67 housed in the wall of breech chamber 2 and which plunger telescopes within a spring as shown in Figure 11. The spring urges the plunger to the Figure 11 position. The outer end of the plunger is connected to a pivoted dog lever 68, the nose of which, when the lever is raised, engages with a notch 69 in one of the fork arms 11, thus locking the fork against forward movement.

When loading takes place, and during the rearward movement of the breech block 10, the dog lever 68 rides along the lower edge of fork arm 11, the spring plunger 67 being yielding to permit this. As soon as the cartridge is extracted the resistance to movement of the lower end of plunger 67 is removed and consequently the dog lever 68 is no longer pressed upwardly and its nose therefore does not engage in notch 69. If, however, for any reason, the round should not be extracted, as soon as the notch 69 passes the nose of dog lever 68, the plunger 67 extends in length and the nose of dog lever 68 engages in notch 69, thus preventing subsequent forward movement of fork arms 11, such as is necessary for the next loading action, until the round of ammunition remaining in the breech has been removed.

The gun being recoil-less may be mounted on any form of stationary or mobile mounting or carriage permitting the necessary traversing and elevating movements of the gun.

I claim:

1. In a recoil-less gun, a barrel, a breech casing including a chamber, said breech casing being provided with a loading port opening from the

rear of its chamber, a breech block movable between breech port-closing position and a predetermined position spaced from closing position, a gas discharge nozzle communicating with the chamber of the breech casing and extending rearwardly from the breech casing, a magazine element including pockets for projectiles and rotatable about said gas discharge nozzle to successively position its pockets in the path of closing movement of the breech block, and means operated by the firing of the gun to reciprocate the breech block and rotate said magazine.

5. A recoil-less gun of the character described in claim 1 wherein the magazine element is of annular form with its pockets arranged in a circumferential series.

15 3. A recoil-less gun of the character described in claim 1 wherein the magazine element is removable.

20 4. A recoil-less gun of the character described in claim 1 including belt means to supply said magazine element with projectiles.

25 5. A recoil-less gun of the character described in claim 1 including a ratchet device secured to the magazine element and a pawl element secured to the breech block reciprocating means.

30 6. A recoil-less gun of the character described in claim 1 wherein the breech block reciprocating means includes a piston operable in a gas cylinder communicating with the barrel bore.

35 7. A recoil-less gun of the character described in claim 1 wherein the breech block reciprocating means includes a piston operable in a gas cylinder communicating with the barrel bore, and said piston is carried by a piston rod having its rearward portion bifurcated to extend through spaced slots in the breech casing and to pass along opposite sides of the breech block.

8. A recoil-less gun of the character described in claim 1 wherein said magazine supporting gas discharge nozzle is positioned below the breech port and a second gas discharge nozzle is positioned above the breech port.

40 9. In a recoil-less gun, a barrel, a breech casing including a chamber, said breech casing being provided with a loading port opening from the rear of its chamber, a breech block movable between breech port closing position and a predetermined position spaced from closing position,

45 50 a gas cylinder on the barrel and in communication with the barrel bore, a piston rod extending from the gas cylinder and rearwardly through the breech casing, a pair of levers pivoted at a point spaced rearwardly of the rear end of the breech casing, said piston rod being operatively connected to said levers so as to move the latter transversely of the breech bore as the piston rod is reciprocated longitudinally of the breech bore, a gas discharge nozzle extending

55 60 rearwardly from the breech casing, a magazine rotatable upon the gas discharge nozzle, and a pawl and ratchet connection between said levers and the magazine whereby the magazine will be given a partial rotation upon each movement of said levers.

65 10. In a recoil-less gun of the character described in claim 1, wherein the breech block is provided with interrupted threads and is rotatable with respect to said breech block operating means, means to hold breech block against rotation during the major portion of its reciprocating movement, interrupted threads in the breech port adapted to engage the threads on the breech block, and means to rotate the breech

block while the latter is moving in engagement with the breech port threads.

11. A recoil-less gun of the character described in claim 10 including a firing pin carried by the breech block and means to move said firing pin forwardly after the breech block is rotated into locked position.

CHARLES DENNISTOUN BURNETT.
